(57) **CLAIM**

The ornamental design for an inverter as shown and described.

DESCRIPTION

FIG. 1 is a front view of an inverter showing our new design; FIG. 2 is a rear view thereof; FIG. 3 is a left view thereof; FIG. 4 is a right view thereof; FIG. 5 is a top view thereof; FIG. 6 is a bottom view thereof; and, FIG. 7 is a perspective view thereof.

The broken lines in the drawings depict portions of the inverter that form no part of the claimed design.
